CONTROL MECHANISM FOR OVEN BURNERS

Charles M. Mayer and John M. Hoff, Mansfield,
Ohio, assignors to The Tappan Stove Company,
Mansfield, Ohio, a corporation of Ohio

Application December 10, 1951, Serial No. 260,905

2 Claims. (Cl. 161—9)

1

This invention relates to a control mechanism for cooking range burners using gaseous fuel and is a modification of the control mechanism shown in our co-pending application filed December 10, 1951, Serial No. 260,904. It is especially designed and adapted for controlling the operation of oven burners in cooking ranges, and may be used in conjunction with a time control mechanism or independently thereof as desired.

The mechanism of the aforesaid co-pending application is designed for use with a main gaseous fuel oven burner which is adapted to be ignited by a constantly burning gaseous fuel oven pilot burner. As long as the oven pilot burner is ignited it is immaterial whether or not the main burner burns constantly during operation. It may be extinguished for some reason, but it will be promptly re-ignited by the oven pilot burner if fuel is supplied thereto. But if the oven pilot burner is extinguished for any reason during operation a very dangerous situation sometimes arises. Let us assume that both the oven pilot burner and the main oven burner are extinguished during operation for some reason. Gas can then flow to the main burner, but since the oven pilot burner is extinguished the main burner will not be ignited and unburned gas will accumulate in the oven which may violently explode when an attempt is made to ignite either the main or pilot burner. It has been found by experience that both the pilot burner and the main burner are frequently extinguished during operation. This is sometimes due to a momentary failure of the gas supply or the slamming of the oven door or to various other reasons.

In order to prevent any accumulation of unburned gas and thus eliminate danger of an explosion therefrom in the event the oven pilot burner is extinguished for any reason during operation a safety control unit by which the supply of gas to the main burner is automatically cut off in the event the pilot burner is extinguished for any reason during operation is provided. The apparatus is so constructed and arranged that this safety control unit is also utilized to turn the gas on and off to initiate and terminate operation of the main oven burner which eliminates the additional manually operable shut off valve generally used in burner control apparatus of this type.

The apparatus includes a main gaseous fuel burner by which the oven in a cooking range is heated. The main burner is adapted to be ig-

nited by a gaseous fuel oven pilot burner which burns both during operation and non-operation of the main burner. During periods of non-operation the supply of gas to the main burner is cut off by the safety control unit which is interposed in a conduit between the gas supply manifold and the burners. During operation gas flows from the manifold into the safety control unit. From the safety control unit gas flows through the main conduit and a standard thermostatically operated oven temperature control valve to the main oven burner.

The safety control unit comprises a control valve which is yieldingly biased to closed position and an electromagnet which when energized is operative to hold the control valve in open position after it has been manually moved from closed to open position, but which is not strong enough to move the control valve from closed to open position. The electromagnet is energized by a multiple thermocouple which is heated by the oven pilot burner and which generates a minute current of the order of from 200 to 250 millivolts. To initiate operation the control valve is manually moved from closed to open position and then released after which the electromagnet holds the valve in open position. Gas can then flow from the manifold to the main burner where it is ignited by the oven pilot burner. The thermocouple, as long as it is heated by the oven pilot burner, maintains the safety control valve in open position. The oven temperature control valve then regulates the supply of gas to the main burner so as to maintain the desired oven temperature. As long as the oven pilot burner is ignited the main burner will burn normally under the control of the oven temperature control valve. But if during operation the oven pilot burner is extinguished for any reason the thermocouple will immediately cool and de-energize the electromagnet which allows the safety control unit to automatically cut off the supply of gas to the main burner. As an example of the manner of operation of the apparatus, let us assume that during operation the oven pilot burner is suddenly extinguished. The thermocouple will then immediately cool, allowing the safety control unit to cut off the flow of gas from the manifold to the main burner. The oven pilot burner must then be manually re-ignited and, after the thermocouple has been re-heated, the control valve manually re-opened to re-initiate operation of the main burner.

In order to extinguish the main burner to terminate operation an interrupter switch in the

circuit between the thermocouple and the safety control valve mechanism is provided. The interrupter switch is yieldingly biased to closed position and when momentarily opened breaks the circuit between the thermocouple and the safety control mechanism which de-energizes the electromagnet and releases the control valve allowing it to cut off the supply of gas to the main burner and thus terminate operation.

In order to adapt the apparatus for automatic control whereby operation of the main burner is automatically initiated at a predetermined set time and is automatically terminated at a predetermined set later time, a normally open solenoid valve is interposed in the fuel supply conduit between the oven temperature control valve and the main burner and a standard electrically operated time control mechanism which includes a normally open switch in series with the solenoid is provided for actuating the solenoid valve. When used the time control mechanism is set as desired which closes the time control switch and energizes the solenoid, thus closing the solenoid valve and then the control valve is manually opened after which the electromagnet will hold the control valve in open position. Gas can then flow past the control valve and the oven temperature control valve, but it cannot yet flow to the main burner as the solenoid valve is now closed. At the set time the time control mechanism opens the time control switch which de-energizes the solenoid and opens the solenoid valve. Gas will then flow to the main burner and be ignited by the oven pilot burner, after which the main burner operates as described in connection with manual control until its operation is terminated by the time control mechanism closing the time control switch at the set time. The closing of the time control switch effects the closing of the solenoid valve and cuts off the supply of gas to the main burner. The interrupter switch is then momentarily opened which effects the closing of the control valve, and the time control mechanism is re-set for manual operation.

In order to heat the thermocouple sufficiently for it to generate enough current to energize the electromagnet in the safety control mechanism the oven pilot burner must be relatively large, burning enough gas to generate approximately 350 B. t. u. per hour. The oven pilot burner should also be approximately this size to assure that it will always ignite the main burner whenever gas is supplied to the main burner. A constantly burning pilot burner of this size mounted in an oven has two disadvantages. First it is costly to operate and second it objectionably heats up the oven when the oven is not in use. In a well insulated oven a constantly burning pilot burner of this size will maintain the temperature in the oven between 100° F. and 110° F.

In the apparatus of the instant invention we eliminate the disadvantages of the aforesaid mechanism by arranging the oven pilot burner to be ignited only during the time the main oven burner is operating and by providing a constantly burning relatively small auxiliary pilot burner which is operative to ignite the oven pilot burner, but which is too small to heat the thermocouple sufficiently for it to generate enough current to energize the electromagnet in the safety control unit. And we also provide an interrupter valve in the safety control unit in addition to the control valve therein. To initiate operation of the main oven burner the control and interrupter valves of the safety control unit are simultane-

ously manually set in position to supply gas to the oven pilot burner while cutting off the supply of gas to the main burner. The valves are manually held in this position until the oven pilot burner has been ignited by the constantly burning auxiliary pilot burner and has heated the thermocouple sufficiently for it to energize the electromagnet in the safety control unit, after which the valves are released. The electromagnet then holds the control valve in the manually set position and the interrupter valve automatically returns to its original position after which gas flows to both the main oven burner and the oven pilot burner. The oven pilot burner then ignites the main burner and both burn together until the operation of the main burner is terminated when both the main oven burner and the oven pilot burner are extinguished. In order to terminate operation the interrupter switch in the thermocouple circuit is momentarily opened as in the aforesaid co-pending application. This breaks the circuit between the thermocouple and the electromagnet and de-energizes the electromagnet. The control valve in the control unit then automatically returns to closed position and cuts off the supply of gas to both the main oven burner and the oven pilot valve. The apparatus is then ready for a subsequent use of the oven.

If a range is to be used in a locality where outside current is available we provide an automatic time control mechanism which is identical in construction and operation with that shown and described in our aforesaid co-pending application.

The principal object of the invention is to provide a simplified control mechanism for gaseous fuel cooking range oven burners which is operative to cut off the supply of fuel to the oven burner in the event the oven pilot burner by which the oven burner is ignited is extinguished for any reason during operation.

Another object of the invention is to provide in an apparatus of the character described a mechanism which acts as a safety control during operation of the oven burners and as a shut off valve during periods of non-operation.

Another object of the invention is to utilize the thermocouple circuit in an apparatus of the character described for maintaining or terminating operation of the burner.

Another object of the invention is to provide an oven burner control mechanism of the character described in which the amount of gas burned by a constantly burning ignition pilot burner is reduced to a minimum.

Another object of the invention is to provide an oven burner control mechanism, having a constantly burning ignition pilot burner, which is so constructed and arranged that the oven will not be unduly heated up during periods of non-operation thereof.

Another object of the invention is to provide a control apparatus of the character described which may be used in conjunction with a time control mechanism or independently thereof as desired.

Other and more limited objects of the invention will be apparent from the following specification and the accompanying drawings forming a part thereof wherein:

Fig. 1 is a diagrammatic layout illustrating our improved control mechanism as applied to a cooking range oven burner using gaseous fuel;

Fig. 2 is an enlarged vertical section through the safety control unit showing it in off or non-operating position; and

Fig. 3 is a view similar to Fig. 2 showing the safety control unit in the position in which it is manually set to initiate operation of the main oven burner.

Referring now to the drawings by reference characters, the numeral 1 indicates a gaseous fuel main burner which is mounted in or in heating relation to a cooking range oven 2. Gaseous fuel is supplied to the burner 1 from a manifold M through a conduit 3. Interposed in the conduit 3 are a safety control unit generally indicated by the numeral 4, and an oven temperature control valve 5. During operation gas flows from the manifold M through the conduit 3 to the safety control unit 4, to be described in detail hereinafter. From the safety control unit 4 the gas flows through the conduit 3 and the oven temperature control valve 5 to the burner 1. The oven temperature control valve 5 is operative to regulate the amount of gas flowing to the main burner 1 in order to maintain the oven at any desired set temperature. The valve 5 is set to any desired temperature by a handle 11 having a pointer 12 which cooperates with a graduated dial 13 in front of the valve 5. The valve 5 is controlled according to the temperature setting by a thermostatic element 14 which is mounted in the oven 2 and is connected to the valve 5 as shown at 15. The oven temperature control valve 5 is of standard well known construction. Consequently it is not shown in detail herein. There are many different constructions available any one of which will work equally well herein. Gas is also supplied to an oven pilot burner 16 through a secondary conduit 17 which extends between the control unit 4 and the oven pilot burner 16. The oven pilot burner 16 is mounted in the oven 2 adjacent the rear end of the main burner 1 in position to ignite the burner 1 when gas is supplied thereto. A relatively small constantly burning auxiliary pilot burner 19 is also mounted in the oven 2 in position to ignite the oven pilot burner 16 when gas is supplied thereto. After the oven pilot burner 16 has been ignited by the auxiliary pilot burner 19 it in turn ignites the main oven burner 1. Gas is constantly supplied to the auxiliary pilot burner 19 from the manifold M through a small conduit 29. A multiple thermocouple 21 is mounted in position to be heated by a flame from the pilot burner 16 and is operative when heated to hold the safety control unit 4 open to supply gas to both the main burner 1 and the oven pilot burner 16, and when cold to release the safety control unit so that it automatically closes and cuts off the supply of fuel to the main oven burner 1 and the oven pilot burner 16.

The oven pilot burner 16 which burns only during the operation of the oven 2 must be of such size as to burn enough gas to generate approximately 350 B. t. u. per hour in order to always assure the igniting of the main burner 1 therefrom and to heat the thermocouple 21 sufficiently to generate the required current. The constantly burning auxiliary pilot burner 19 being used only to ignite the oven pilot burner 16 is relatively small generating approximately 50 B. t. u. per hour which is not sufficient to appreciably heat up the oven during periods of non-operation thereof.

An electric circuit between the thermocouple 21 and the safety control unit 5 is established by a copper tube 22 which encloses an insulated wire 23. The wire 23 is severed between the thermocouple 21 and the safety control unit 4 and

an interrupter 24 having terminals 25 and 26 is interposed between the severed ends. One of the severed ends of the wire 23 is connected to the terminal 25 and the other severed end is connected to the terminal 26. A normally closed push button switch 27 is mounted in a casing 28 secured to a plate 29 in the cooking range. The switch 27, which is yieldingly biased to closed position by a spring 30, comprises the contacts 31 and 32 and the bar 33 to which a push button 34 is connected. The terminal 25 of the interrupter 24 is connected to the contact 31 of the switch 27 by the lead 23a, and the terminal 26 of the interrupter 24 is connected to the contact 32 of the switch 27 by the lead 23b. The purpose and function of the switch 27 will be described hereinafter.

The construction of the safety control valve unit 4 will now be described, reference being had to Figs. 2 and 3 of the drawings. This unit comprises a casing 35 having a chamber 36 in one end thereof and a chamber 37 in the other end thereof. The chambers 36 and 37 are connected by a bore 38 of reduced diameter. A valve seat 39 is located at one end of the bore 38 and a similar valve seat 40 is located at the other end of the bore 38. The chamber 36 is closed by a removable cap 41 and the chamber 37 is closed by a removable cap 42. A sleeve 43, having end walls 44 and 45, is carried by the cap 41 and extends into the chamber 36. A valve stem 46 which is slidably mounted in a bushing 47 carried by the end wall 45 of the sleeve 43, extends from the chamber 36 into the sleeve 43. A control valve 48 of suitable material is secured to one end of the valve stem 46 within the chamber 36, and an armature 49 is secured to the other end of the stem 46 within the sleeve 43. A spring 50 disposed about the valve stem 46 between the valve 48 and the end wall 45 of the sleeve 43 normally holds the control valve 48 against the valve seat 39. An electromagnet 51 is secured to one end of a hollow exteriorly threaded stud 52 which extends cut through aligned apertures in the end wall 44 of the sleeve 43, and in the end of the cap 41. A nut 53 screwed onto the outer portion of the stud 52 securely holds the magnet 51 and the sleeve 43 in place. The legs of the magnet 51 have a winding 54 thereon one end of which is connected to the tube 22 and the other end of which is connected to the wire 23 in the tube 22. The tube 22 is inserted into the hollow stud 52 and is held in place by a screw fitting 52a. A sleeve 55 is screwed into a threaded recess in the end of the cap 42, as indicated at 56, and extends into the chamber 37 a slight distance. One end of the sleeve 55 is closed by an end wall 57, and the other end which is open registers with a circular aperture 58 in the end wall of the cap 42. A plunger 59 is slidably mounted in the sleeve 55 and extends out through the aperture 58 in the cap 42. A stem 62 which is secured to the inner end of the plunger 59 extends out through an aperture 63, in the end wall 57 of the sleeve 55, and through the chamber 37 and into the bore 38. The stem 62 has a collar 64 rigidly secured thereon between the end wall 57 and the outer end of the stem. An interrupter valve 65 of suitable material is slidably mounted upon the stem 62 between the end wall 57 of the sleeve 55 and the collar 64. The valve 65 is adapted to engage the valve seat 40 to cut off the flow of gas into the chamber 37 during the initiation of operation as will be hereinafter described. A compression spring 66

disposed about the stem 62 between the end wall 57 and the valve disc 65 normally yieldingly holds the valve 65 against the collar 64. A compression spring 67 which is stronger than the spring 66 is disposed about the stem 62 within the sleeve 55 between the inner face of the end wall 57 and the inner end of the plunger 59. The spring 67 is operative to return the plunger 59, stem 62 and valve 65 from the position shown in Fig. 3 back to their normal position as shown in Fig. 2, against the resistance of the spring 66. A port 68 in the casing 35 provides communication between the chamber 36 and the conduit 3 to allow gas to flow from the manifold M through the conduit 3 into the chamber 36. During normal operation of the main burner 1 gas flows from the chamber 36 through the reduced intermediate bore 38 and into the chamber 37. A port 69 which establishes communication between the conduits 17 and the bore 38 is provided to supply gas to the pilot burner 16; and a port 70 establishes communication between the chamber 37 and the conduit 3 to permit the flow of gas from the chamber 37 to the main burner 1 through the oven temperature control valve 5.

The operation of the apparatus under manual control will now be described. To initiate operation of the main oven burner 1 it is only necessary to momentarily manually hold the plunger 59 and then release it. The depressing of the plunger 59 shifts the mechanism of the safety control unit 4 from the position shown in Fig. 2 to the position shown in Fig. 3 to which position gas flows through the conduit 17 to the oven pilot burner 16, but is cut off from the main oven burner 1 by the interrupter valve 65. The oven pilot burner 16 is then ignited by the constantly burning auxiliary pilot burner 19 and heats the thermocouple 21. As soon as the thermocouple 21 is sufficiently heated, which takes but a few seconds, the plunger 59 is released, it being understood that the plunger 59 must be held depressed until the thermocouple has been sufficiently heated. As soon as the plunger 59 is released the spring 67 will return the plunger 59, stem 62, and interrupter valve 65 back to their original position, as shown in Fig. 2; and the electromagnet 51 being now energized by the thermocouple 21 will retain the control valve 48 in the chamber 36 in open position as shown in Fig. 3. Gas will now flow to the main burner 1 when it is ignited by the oven pilot burner 16. Under normal conditions the main burner 1 will now operate under control of the oven pilot burner 16 and the oven temperature control valve 5 until the operation thereof is manually terminated. To terminate operation of the burner 1 it is only necessary to momentarily depress the push button 34 of the switch 27 which opens the switch 27 and breaks the circuit between the thermocouple 21 and the winding 54 of the electromagnet 51. The breaking of this circuit de-energizes the electromagnet 51 after which the spring 50 returns the control valve 48 back from the open position shown in Fig. 3 to the closed position shown in Fig. 2 which cuts off the supply of gas to both the main burner 1 and the oven pilot burner 16 and terminates operation.

If during operation the oven pilot burner 16 is extinguished for any reason and is not immediately reignited by the auxiliary pilot burner 19 the thermocouple 21 will quickly cool and de-energize the electromagnet 51, after which the spring 50 will move the control valve 48 to closed

position and cut off the supply of gas to both the main burner 1 and the oven pilot burner 16, thus preventing any possibility of unburned gas escaping into the oven. To re-initiate operation after it has been terminated by the extinguishment of the oven pilot burner 16 the plunger 59 must again be manually depressed as previously described. If for any reason the auxiliary pilot burner 19 is not ignited when the plunger 59 is depressed to initiate operating, operation cannot be initiated since the oven pilot burner 16 must be ignited before gas can be supplied to the main burner 1 and the oven pilot burner 16 depends upon the auxiliary pilot burner 19 for ignition. In this case a small amount of unburned gas will escape through the oven pilot burner 16 into the oven 2 as long as the plunger 59 is held depressed, but this will not be enough to be dangerous as the plunger 59 is only held depressed a few seconds when initiating operation.

In order to adapt the apparatus for automatic control in localities where outside current is available we interpose a normally open solenoid valve 75 in the conduit 3 between the oven temperature control valve 5 and the burner 1, and we provide a standard electrically operated time control mechanism 76 which is adapted to open and close a switch 77 at predetermined set times. The switch 77 is mounted in series with a solenoid 78 which is operative when energized to maintain the normally open valve 75 closed.

When used the time control mechanism 76 is first set to initiate operation of the burner 1 at a predetermined time and to terminate operation thereof at a predetermined later time. The setting of the time control 76 closes the normally open switch 77 which energizes the solenoid 78 which then closes the normally open valve 75. Then the plunger 59 of the safety control mechanism 4 is momentarily held depressed which opens the control valve in the chamber 36 and supplies gas to the oven pilot burner 16. After the plunger 59 is released the electromagnet 51, which has been energized by the igniting of the oven pilot burner 16 retains the control valve in open position. Gas can now flow from the manifold M through the safety control mechanism 4, but cannot yet reach the burner 1 as the normally open valve 75 in the conduit 3 is now closed. At the set time the time control 76 opens the switch 77 which de-energizes the solenoid 78 and opens the valve 75. Gas will now flow to the burner 1 which is then ignited by the oven pilot burner 16. Under normal conditions the burner 1 will operate under the control of the oven temperature control valve 5 until at the set time the time control 76 again closes the switch 77 which energizes the solenoid 78 and closes the valve 75 thus cutting off the supply of gas to the burner 1 and terminating operation thereof. The push button switch 6 is then momentarily manually opened which breaks the circuit between the thermocouple 20 and the electromagnet 51 and de-energizes the magnet 51. The control valve in the chamber 36 is then closed by the spring 50. The time control 76 is then set for manual control which opens the switch 77 and de-energizes the solenoid 78 thus opening the valve 75. The apparatus is now ready for the next operation of the burner 1.

If during automatic operation the pilot burner 16 is extinguished for any reason the safety control unit 4 will cut off the supply of gas to the burner 1 as explained in connection with manual control.

From the foregoing it will be apparent to those

skilled in this art that we have provided a very simple and efficient apparatus for accomplishing the objects of the invention.

It is to be understood that we are not limited to the specific construction shown and described herein as various modifications may be made therein within the scope of the appended claims.

What is claimed is:

1. In a control apparatus of the character described the combination of a chamber, a fuel supply manifold, a gaseous fuel main burner mounted in said chamber, a fuel supply conduit through which gaseous fuel is supplied to said main burner from said manifold, a relatively large oven pilot burner disposed in said chamber closely adjacent said main burner and operative when ignited to ignite said main burner when fuel is supplied to said main burner, a constantly burning relatively small auxiliary pilot burner disposed in said chamber closely adjacent said oven pilot burner and operative to ignite said oven pilot burner when fuel is supplied to said oven pilot burner, a safety control unit interposed in said conduit between said manifold and said main burner, a secondary conduit through which fuel is supplied to said oven pilot burner, a control valve operative when closed to cut off the supply of fuel to said main burner and said oven pilot burner and when open to admit fuel to said main burner and said oven pilot burner incorporated in said safety control unit, means yieldingly biasing said control valve to closed position, means by which said control valve is manually moved to open position, an electromagnet operative when energized to maintain said control valve in open position after said control valve has been manually moved to open position incorporated in said safety control unit, a thermocouple mounted in said chamber in position to be heated by said relatively large oven pilot burner, an electric circuit between said thermocouple and said electromagnet through which said electromagnet is energized by said thermocouple when said thermocouple is heated, a normally closed switch in said electric circuit, said switch being operative when opened to break said circuit and de-energize said electromagnet.

2. In a control apparatus of the character described the combination of a chamber, a fuel supply manifold, a gaseous fuel main burner mounted in said chamber, a fuel supply conduit through which gaseous fuel is supplied to said main burner from said manifold, or relatively large oven pilot burner disposed in said chamber closely adjacent said main burner and operative when ignited to ignite said main burner when fuel is supplied to said main burner, a constantly burning relatively small auxiliary pilot burner disposed in said chamber closely adja-

cent said oven pilot burner and operative to ignite said oven pilot burner when fuel is supplied to said oven pilot burner, a safety control unit interposed in said conduit between said manifold and said main burner, a secondary conduit through which fuel is supplied to said oven pilot burner, a control valve operative when closed to cut off the supply of fuel to said main burner and said oven pilot burner and when open to admit fuel to said main burner and said oven pilot burner incorporated in said safety control unit, means yieldingly biasing said control valve to closed position, means by which said control valve is manually moved to open position, an electromagnet operative when energized to maintain said control valve in open position after said control valve has been manually moved to open position incorporated in said safety control unit, a thermocouple mounted in said chamber in position to be heated by said relatively large oven pilot burner, an electric circuit between said thermocouple and said electromagnet through which said electromagnet is energized by said thermocouple when said thermocouple is heated, a normally closed switch in said electric circuit, said switch being operative when opened to break said circuit and de-energize said electromagnet, a normally open valve interposed in said conduit between said safety control unit and said main burner, a solenoid operative when energized to maintain said normally open valve closed, a normally open switch by which the energization of said solenoid is controlled, and a time control mechanism adapted to be manually set for either manual or automatic control of said main burner, and operative connections between said time control mechanism and said normally open switch through which said normally open switch is opened and closed by said time control mechanism being operative upon the setting thereof for automatic control of said main burner to close said normally open switch and at a predetermined later time to open said normally open switch and at a still later time to close said normally open switch and to again open said normally open switch upon the resetting of said time control mechanism for manual control of said burner.
